Frederick S. Stell,
ATTORNEY.

UNITED STATES PATENT OFFICE.

RAYMOND W. KEELER, OF GALION, OHIO, ASSIGNOR TO THE GALION IRON WORKS & MFG. CO., OF GALION, OHIO, A CORPORATION OF OHIO.

EXHAUST NOZZLE FOR STEAM BOILERS.

Application filed May 14, 1923. Serial No. 638,916.

To all whom it may concern:

Be it known that I, RAYMOND W. KEELER, a citizen of the United States, residing at Galion, in the county of Crawford and 5 State of Ohio, have invented certain new and useful Improvements in Exhaust Nozzles for Steam Boilers, of which the following is a specification.

This invention relates to boilers of a vertical type, and particularly to those boilers having an exhaust steam pipe discharging into the stack to cause a draft through the fire tubes of the boiler.

In boilers of this construction the cross 15 sectional area of the boiler is relatively large and that of the stack is relatively small so that those tubes which are out of line with the smoke stack are practically useless as flues because the exhaust does not pull a 20 draft through them or does not exert its whole force to secure a draft through these tubes. Therefore, those flues directly under the smoke stack are very liable to be burned out.

25 One of the objects of my invention is to overcome this condition by providing a nozzle so constructed that the exhaust steam as it leaves the nozzle will be projected radially outward over all the fire tube ends, 30 the nozzle being further so constructed, however, that some of the exhaust steam will pass directly from the nozzle into the stack at a high velocity so as to pick up the steam which has been spread radially outward and cause a draft through all of the 35 flues instead of merely those flues which are directly under the smoke stack.

My invention is illustrated in the accompanying drawings, wherein:—

40 Figure 1 is a vertical sectional view of a boiler having an exhaust nozzle constructed in accordance with my invention;

Figure 2 is a top plan view of the nozzle;

45 Figure 3 is a fragmentary elevation of the upper end of the nozzle;

Figure 4 is a sectional view of the nozzle on the line 4—4 of Figure 2;

Figure 5 is a section on the line 5—5 of Figure 4.

50 Referring to these drawings, 10 designates the outer shell of a vertical boiler of any suitable type and having the dome 11 and the smoke stack 12. Opening through the head 13 are the fire tubes 14. So far

the construction is that of an ordinary 55 standard vertical boiler.

Extending radially inward through the wall of the shell 10 is a steam pipe 15 which is connected to any suitable source of steam under high pressure. This pipe extends 60 radially inward to the center of the dome 11 and is there connected to an angular exhaust nozzle 16 which extends upward in axial alignment with the axis of the stack 12. This exhaust nozzle, as illustrated in 65 Figure 1, is screw-threaded at its butt end to engage the pipe 15 and is then turned so that the axis of the upwardly extending portion is at right angles to the axis of 70 the horizontal portion, this upwardly extending portion 17 of the nozzle being gradually tapered so that in actual practice it will, for instance, have an exterior diameter adjacent the lower end of the portion 17 of $1\frac{1}{2}$ ", while at the upper end of 75 the nozzle the diameter will only be 1". Of course, these dimensions are merely given to illustrate the extent to which the nozzle tapers upward.

Adjacent its upper end the nozzle is 80 formed with a plurality of openings 18 which extend longitudinally of the nozzle to any desired extent but terminate short of the upper end of the nozzle. These openings also extend circumferentially around 85 the nozzle and, as illustrated, there are three of these openings, but I do not wish to be limited to this. Above the openings the nozzle has a relatively solid upwardly flaring end 19 with a central aperture 20. As 90 the exhaust travels through the pipe 15 and through the nozzle, it will strike the portion 19, which constitutes a deflector plate, and the exhaust steam will be deflected out through the openings 18 in a 95 fan shape which will practically extend across almost the entire upper ends of the flues or the entire surface of the web 13. The aperture 20 in the upper end of the nozzle will let some of the exhaust steam 100 pass through at a high velocity and this high velocity stream will pick up the steam which has been ejected laterally and cause a draft through all of the several fire tubes or flues of the boiler instead of merely 105 through those which are directly under the smoke stack.

While I have illustrated a particular

form of nozzle, I do not wish to be limited thereto, as the nozzle might have a different form in detail without departing from the spirit of the invention.

5 I claim:

1. A nozzle for exhaust steam pipes, the nozzle at its discharge end being formed to provide a web extending transversely with relation to the axis of the nozzle, said 10 web having a central aperture, the side wall of the nozzle inward of the web being provided with a plurality of longitudinally and circumferentially extending openings, the outer wall of the web forming one wall 15 of each of said openings, said outer wall being beveled inward and centrally toward the axis of the nozzle.
2. The combination with a vertical boiler having vertical fire tubes, a dome disposed 20 above the fire tubes and a centrally disposed stack mounted on the dome, of means for causing a forced draft through the fire tubes including an exhaust steam pipe ex- 25 tending through the side wall of the dome to the axial center thereof and having a nozzle on its end extending upward con-

centric to the central axis of the stack, said nozzle being gradually tapered upward, the upper extremity of the nozzle being formed with a relatively small, centrally located 30 outlet opening, the side walls of the nozzle below said opening having vertically and circumferentially extending apertures formed to cause the discharge of steam in the form of a fan.

3. The combination with a vertical boiler having fire tubes and a dome above the fire tubes and having a stack, of an exhaust steam pipe entering the dome and having a nozzle discharging toward the stack, said 40 nozzle at its upper end being formed to provide a web partially obstructing the nozzle but formed with a central opening, the side wall of the nozzle below the web being provided with a plurality of longitudinally 45 and circumferentially extending openings, the outer face of the web forming the upper walls of said openings and being upwardly and outwardly inclined.

In testimony whereof I affix my signature.

RAYMOND W. KEELER.
